(57) **CLAIM**

The ornamental design for an ergonomic electric eraser and stand, substantially as shown and described.

DESCRIPTION

FIG. 1 is a top view of ergonomic electric eraser and stand showing the new design;

FIG. 2 is a front view thereof;

FIG. 3 is a right side view thereof; the left side view being a mirror image;

FIG. 4 is a rear view thereof;

FIG. 5 is a right side elevational view thereof in an exploded condition;

FIG. 6 is a front view of the ergonomic electric eraser shown separately for ease of illustration;

FIG. 7 is a bottom plan view of FIG. 6;

FIG. 8 is a right side view of FIG. 6, the left side view being a mirror image;

FIG. 9 is a top plan view of FIG. 6;

FIG. 10 is a rear view of FIG. 6;

FIG. 11 is a top plan view of the ergonomic electric eraser stand shown separately for ease of illustration;

FIG. 12 is a front view of FIG. 11;

FIG. 13 is a right side view of FIG. 11, the left side view being a mirror image;

FIG. 14 is a rear view of FIG. 11; and,

FIG. 15 is a bottom plan view of FIG. 11.
